FISHING FLOAT

Christie L. Hansen, P.O. Box 12, Port Sulphur, La.

Filed Nov. 5, 1962, Ser. No. 72,385

Term of patent 14 years

(Cl. D31—4)

FIG. 1

FIG. 2

FIG. 3

FIG. 4

FIG. 5

FIG. 6

FIG. 1 is a side elevation of a fishing float;
FIG. 2 is a side elevation of the fishing float shown in FIG. 1, but rotated about 90° about its vertical axis;
FIG. 3 is a side elevation of the fishing float shown in FIG. 1, but rotated about 180° about its vertical axis;
FIG. 4 is a side elevation of the fishing float shown in FIG. 1, but rotated about 270° about its vertical axis;
FIG. 5 is an end elevation of the upper end of the float shown in FIG. 4;
FIG. 6 is an end elevation of the bottom end of the float of FIG. 2.

I claim:

The ornamental design for a fishing float, substantially as shown.
